United States Patent Office

Des. 190,479
Patented June 6, 1961

190,479

ARTICLE HOLDER FOR VEHICLE SUN VISORS

Everett J. Wax, Brooklyn, N.Y., assignor to Sealfast Electronics Corporation, New York, N.Y., a corporation of New York

Filed Feb. 18, 1960, Ser. No. 59,443

Term of patent 7 years

(Cl. D14—6)

FIG. 1

FIG. 2

FIG. 3

FIG. 4

FIG. 1 is a front view of an article holder for vehicle sun visors showing my new design;

FIG. 2 is a rear view thereof;

FIG. 3 is a top view thereof; and

FIG. 4 is an end view thereof on a reduced scale.

The umbrella shown in broken lines in FIGS. 1, 2 and 4 is included for illustrative purposes only.

I claim:

The ornamental design for an article holder for vehicle sun visors, substantially as shown and described.
